LOUNGE CHAIR

Leif Blodee, Holland, Mich., assignor to American Seating Company, Grand Rapids, Mich.

Filed June 22, 1973, Ser. No. 372,854

Term of patent 14 years

Int. Cl. D6—01

U.S. Cl. D6—38

FIG. 1

FIG. 2

FIG. 3

FIG. 4

FIG. 5

FIG. 6

FIG. 1 is a rear perspective view of a lounge chair showing my design wherein the seat and backrest cushions are tufted;

FIG. 2 is an upper perspective view of the chair of FIG. 1 taken from the front and left side;

FIG. 3 is an upper perspective view of an alternative embodiment of the chair of FIG. 1, without tufting of the cushions, taken from the side and front;

FIG. 4 is an upper perspective view taken from the rear and right side of a modification of the chair of FIG. 1 with arms and tufting of the cushions;

FIG. 5 is an upper perspective view of the chair of FIG. 4 taken from the right side and front; and

FIG. 6 is an upper perspective view of the inventive chair with arms and without tufting, taken from the front left side.

I claim:

The ornamental design for a lounge chair, as shown and described.
